OUTPUT STAGES FOR LOW-FREQUENCY AMPLIFIERS COMPRISING TWO LOUDSPEAKERS

Johann Kump, Vienna, Austria, assignor, by mesne assignments, to North American Philips Company, Inc., New York, N. Y., a corporation of Delaware

Application April 9, 1956, Serial No. 577,113

Claims priority, application Austria May 5, 1955

5 Claims. (Cl. 179—1)

The present invention relates to an amplifier output stage circuit arrangement. More particularly, the invention relates to output stages of low-frequency amplifiers comprising two loudspeakers, which are preferably intended for the reproduction of low frequencies and high frequencies, respectively, of the acoustic spectrum with the use of one or more screen-grid tubes as output tubes.

The object of the invention is in such output stages to obtain a considerable decrease in distortion in the high-frequency range. It is common knowledge that distortion in the high-frequency range is subjectively very troublesome to the ear. Consequently, in the reproduction of an acoustic frequency-band, which must comprise the whole acoustic region up to about 15 kilocycles per second, the requirements in regard to freedom of distortion must be much higher than in the reproduction of an acoustic frequency-band which is limited in the direction of high frequencies.

On account of their high output, the present types of output stages of low-frequency amplifiers substantially utilize screen-grid tubes and more particularly pentodes. As appears from the characteristic curves of such tubes, the new tones experienced therein as distortion substantially comprise the third harmonics and combination tones of higher order and hence high tones. Insofar as loudspeakers are used for the acoustic reproduction, which cannot or substantially cannot reproduce the high-frequency range, the loudspeaker suppresses part of this distortion. If use is made of a loudspeaker reproducing the frequencies up to 15 kilocycles per second, or if two or more loudspeakers are used, which are each preferably intended for the reproduction of the low-frequency ranges (low-tone loudspeaker) and the high-frequency ranges (high-tone loudspeaker), respectively, the high frequencies produced in the amplifier are no longer suppressed and thus become manifest with maximum effect.

The behaviour of triodes is more favorable than that of screen-grid tubes (pentodes) in regard to distortion, but their low output constitutes a great disadvantage.

A circuit is already known, which has been adopted in literature as an "ultra-linear circuit" (cf. British Patent No. 496,883), in which it is endeavoured to combine the advantages of triodes and screen-grid tubes. In this circuit, the screen-grid of the output tube, instead of being applied to cathode potential for alternating voltage, as is usually the case, has applied to it part of the alternating anode voltage. This may be accomplished, for example, by connecting the screen-grid directly to a tapping point on the primary winding of the output transformer included in the anode circuit of the output tube, so that the screen grid at the same time also receives the required

2

direct voltage. Due to this circuit, which in fact means the introduction of a negative feedback coupling, the tube acquires properties located between those of a triode and of a tube in screen grid connection. The distortion is reduced at the expense of the output and evenly for any frequency.

The invention is based on the consideration that a decreased output may be taken into the bargain for high-frequencies, if the output remains unchanged in the low-frequency and intermediate-frequency range, since the strength of the subjective impression of sound is determined substantially by the reproduction of this range. If this range is reproduced by a loudspeaker which is insensitive to high frequencies and hence by a low-tone loudspeaker, a higher distortion factor is permissible for this range, since, as mentioned before, the distortion which consists of very high tones is not audible. However, the high-frequency range, which must of course not be absent in the reproduction of the whole acoustic spectrum, must then be reproduced by a separate high-tone loudspeaker, in which the distortion factor must be as low as possible. A decreased output in the reproduction of this range may be taken into the bargain, since it is substantially not audible.

It has previously been suggested to supply the low and high frequencies separately to two different output tubes, constituted by a triode and a pentode, respectively. However, this arrangement requires the use of a comparatively large number of circuit elements.

According to the invention, in the output stage of a low-frequency amplifier having two loudspeakers preferably intended for the reproduction of low frequencies and high frequencies, respectively, of the acoustic spectrum with the use of one or more screen-grid tubes as output tubes, the impedances which are effected by the loudspeakers in the anode circuits of the tubes are connected in series. The anode of each tube is connected to the impedance constituted by the low-tone loudspeaker, which impedance is shunted by a capacitor of a value such that the resistance of the capacitor for high frequencies is low with respect to this impedance. The screen-grid for alternating voltage is connected between the two impedances.

In order that the invention may be readily carried into effect it will now be described, by way of example, with reference to the accompanying drawing, wherein:

Fig. 1 is a schematic diagram of an embodiment of the circuit arrangement of the present invention; and

Fig. 2 is a schematic diagram of another embodiment of the circuit arrangement of the present invention.

In the circuit arrangement of Fig. 1, the alternating voltage to be amplified is applied to control grid 2 of pentode 1. The control grid receives the required biasing potential in the usual manner by connecting cathode 3, via a resistor 4 and a capacitor 5, to ground potential. Suppressor grid 6 is connected to the cathode. The circuit leading from anode 7 to battery 8 is completed via the primary winding 9 of an output transformer 10, the secondary winding 11 of which is connected to a low-tone loudspeaker 12, and via the primary winding 13, connected in series with the winding 9, of an output transformer 14, the secondary winding 15 of which is connected to a high-tone loudspeaker 16. The primary winding 9 is shunted by a capacitor 17 having a value such that it constitutes a very low impedance for high

frequencies and hence substantially short-circuits output transformer 10 for these frequencies. The screen grid 18 of pentode 1 is connected directly to a point 19 of the anode circuit located between the two primary windings 9 and 13. The primary impedance 13 may be comparatively low, since an output transformer for a high-tone loudspeaker is concerned. For low frequencies, the screen grid 18 is thus substantially connected to the constant positive potential determined by battery 8, so that tube 1 operates as a screen-grid tube for low frequencies. Its output is very satisfactory. However, the distortion, which is greater in screen grid tubes, is not completely heard in the loudspeaker, since the loudspeaker 12 is a low-tone loudspeaker. For high frequencies, the transformer 10 is substantially short-circuited by capacitor 17, which implies that the anode 7 and the screen-grid 18 are substantially directly connected to one another for these frequencies. The tube 1 thus operates as a triode for these frequencies and, while having a lower output for these frequencies, leads to a reproduction with a very low distortion factor. It is common knowledge in engineering to choose the proportioning such that the cooperation of the two loudspeakers yields the desired substantially rectilinear reproduction curve of the whole arrangement. Of course, instead of utilizing the separate loudspeakers 12 and 16, use may be made of groups of low-tone and high-tone loudspeakers each comprising a plurality of loudspeakers; it naturally being possible only to combine loudspeakers of the same kind into one group.

In the embodiment shown in Fig. 1, the impedances are constituted by the transformers loaded with the loudspeakers. The situation remains unchanged, if use is made of loudspeakers having impedances such that they can be included in the circuit without the use of transformers. Neither does a connection of the impedances free from direct current change anything in the fundamental operation.

Fig. 2 shows the use of the arrangement according to the invention in push-pull connection. The two push-pull tubes 20 and 21 are shown only diagrammatically and the two halves 22 and 23 of the output transformer 24 for the low-tone loudspeaker 25 are not connected directly to one another. Each half is bridged by a capacitor 26, 27, respectively, for high frequencies. The center tap 28 of the primary winding of output transformer 31 for the high-tone loudspeaker 32, which winding consists of two halves 29 and 30, is connected to the positive terminal of the source of anode supply. The anodes 34 and 35 of the tubes 20 and 21 are each connected to one end of the primary windings 22 and 23, the other ends of these windings being connected to the primary windings 29 and 30. The screen-grid 36 of tube 20 is connected to point 37 between the windings 22 and 29, the screen grid 38 of tube 21 being connected to point 39 between the windings 23 and 30. The operation of the circuit arrangement of Fig. 2 is similar to that of the circuit shown in Fig. 1.

While the invention has been described by means of specific examples and in specific embodiments, I do not wish to be limited thereto for obvious modifications will occur to those skilled in the art without departing from the spirit and scope of the invention.

What is claimed is:

1. A low frequency amplifier output circuit arrangement, comprising an electron discharge device having an anode, a cathode and a plurality of grids including a screen grid, a first loudspeaker system for reproducing sound in a substantially low audio frequency range, a second loudspeaker system for reproducing sound in a substantially high audio frequency range, means for applying an input signal to one of said grids, means connecting said first and second loudspeaker systems in series circuit arrangement and to said anode, said first loudspeaker system being interposed between said anode and said second loudspeaker system, a capacitor having a reactance value which is substantially low with respect to

the impedance of said first loudspeaker system at said high audio frequency range, means connecting said capacitor in shunt across said first loudspeaker system, and means connecting said screen grid to a common point between said first and second loudspeaker systems in said series circuit arrangement.

2. A low frequency amplifier output circuit arrangement, comprising an electron discharge tube having an anode, a cathode and a plurality of grids including a screen grid, a first loudspeaker for reproducing sound in a substantially low audio frequency range, a second loudspeaker for reproducing sound in a substantially high audio frequency range, means for applying an input signal to one of said grids, first and second coupling transformers each comprising primary and secondary windings, means connecting said first and second primary windings in series circuit arrangement and to said anode, said first primary winding being interposed between said anode and said second primary winding, means coupling said first loudspeaker to said first secondary winding, means coupling said second loudspeaker to said second secondary winding, a capacitor having a reactance value which is substantially low with respect to the impedance of said first primary winding at said high audio frequency range, means connecting said capacitor in shunt across said first primary winding, and means connecting said screen grid to a common point between said first and second primary windings in said series circuit arrangement.

3. A low frequency amplifier output circuit arrangement, comprising a pair of discharge tubes connected in push-pull arrangement each having an anode, a cathode and a plurality of grids including a screen grid, a first loudspeaker system for reproducing sound in a substantially low audio frequency range, a second loudspeaker system for reproducing sound in a substantially high audio frequency range, means for applying an input signal to selected grids of said tubes, means connecting said first and second loudspeaker systems in series circuit arrangement between the anodes of said tubes, said first loudspeaker system being interposed between said anodes and said second loudspeaker system, a capacitor having a reactance value which is substantially low with respect to the impedance of said first loudspeaker system at said high audio frequency range, means connecting said capacitor in shunt across said first loudspeaker system, and means connecting said screen grid to a common point between said first and second loudspeaker systems in said series circuit arrangement.

4. A low frequency amplifier output circuit arrangement, comprising a pair of discharge tubes connected in push-pull arrangement each having an anode, a cathode and a plurality of grids including a screen grid, a first loudspeaker for reproducing sound in a substantially low audio frequency range, a second loudspeaker for reproducing sound in a substantially high audio frequency range, means for applying an input signal to selected grids of said tubes, a first coupling transformer comprising first and second primary windings and a secondary winding, a second coupling transformer comprising primary and secondary windings, means connecting the primary windings of said first and second transformers in series circuit arrangement between the anodes of said tubes, the primary winding of said second transformer being interposed between the first and second primary windings of said first transformer, means coupling said first windings of said first transformer to said first secondary winding and means coupling said second loudspeaker to said second secondary winding, a first capacitor having a reactance value which is substantially low with respect to the impedance of the first primary winding of said first transformer at said high audio frequency range, a second capacitor having a reactance value which is substantially low with respect to the impedance of the second primary winding of said first transformer at said high audio frequency

range, means connecting said first capacitor in shunt across said first primary winding of said first transformer, means connecting said second capacitor in shunt across said second primary winding of said first transformer, means connecting the screen grid of said first tube to a common point between said first primary winding of said first transformer and the primary winding of said second transformer in said series circuit arrangement, and means connecting the screen grid of said second tube to a common point between said second primary winding of said first transformer and the primary winding of said second transformer in said series circuit arrangement.

5. A circuit arrangement as claimed in claim 4, further comprising a center tap on the primary winding of said second transformer and means for applying a supply voltage to said tap.
